UNITED STATES PATENT OFFICE.

FREDERICK GOERTZ, OF NEWARK, AND RUSSELL WHITCOMB, OF ELIZABETH, NEW JERSEY, ASSIGNORS TO AUGUST GOERTZ AND COMPANY, A CORPORATION OF NEW JERSEY.

CONTAINER.

1,345,359.

Specification of Letters Patent. Patented July 6, 1920.

Application filed June 6, 1919. Serial No. 302,205.

To all whom it may concern:

Be it known that we, FREDERICK GOERTZ, a citizen of the United States, residing at Newark, county of Essex and State of New Jersey, and RUSSELL WHITCOMB, a citizen of the United States, residing at Elizabeth, in the county of Union and State of New Jersey, have invented certain new and useful Improvements in Containers; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in cases or boxes adapted to contain face-powders; and, the present invention has reference, more particularly, to a novel construction of toilet article in the form of a double-compartment powder-box or case, adapted to contain powders, in the form of compacts or cakes, or otherwise, and of different colors, one compact being red or pink rouge, and the other compact being a white face-powder, the box or case being provided with means for keeping the variously colored rouge and face-powder separate from each other, and, furthermore, to provide a box or case with a cake-retaining means which can be readily detached and separated from above the compartments of the box or case, for the removal from or replacing within the said compartments of the usual compacts or cakes of rouge and face-powder.

The invention has for its principal object to provide a novel and simply-constructed powder-box or case of the general character hereinafter more fully set forth, and for the purposes above stated, providing a box or casing in which variously colored rouge and face-powder, as compacts or in cake-form or otherwise, may be placed for use, and may be removed therefrom, if desired, without any possibility of the powder of one color becoming mixed or intermingling with the powder of another color, or of the color of the rouge spoiling the color of the face-powder.

The present invention has for its further

object to provide a powder-box or casing of the character stated with a guard or retaining means for holding the compacts or cakes of different colors in their separated relation within the compartments of the box or case, and furthermore, to provide the main body of the box or case with a dividing or separating wall which serves as a carrier with which said guard or retaining means is adapted to be brought into frictional holding or retaining engagement, but may be readily detached for removal from the box or case, when necessary.

Other objects of the present invention not at this time more particularly enumerated will be clearly understood from the following detailed description of the present invention.

With the various objects of the present invention in view, the said invention consists, primarily, in the novel powder-box hereinafter set forth; and, the present invention consists, furthermore, in the novel arrangements and combinations of the various devices and parts, as well as in the details of the construction of the said parts, all of which will be more fully described in the following specification, and then finally embodied in the clauses of the claims which are appended to and which form an essential part of the said specification.

The invention is fully illustrated in the accompanying drawings, in which:—

Fig. 1 is a plan view of a powder-box or case showing one embodiment of the principles of the present invention, the box or case being represented with its lid opened, and illustrating in connection with the main body of the box or case, the compact or powder-cake retaining means in its position for retaining the rouge and powder-cakes in place.

Fig. 2 is a longitudinal vertical sectional representation of the several parts represented in said Fig. 1, but showing the lid in its closed position.

Fig. 3 is a transverse vertical section of the device, said section being taken on line 3—3 in said Fig. 2; and Fig. 4 is a similar section, taken on line 4—4 in said Fig. 2.

Fig. 5 is a plan view of the powder-box or case, with its lid in opened position, and with the compact or powder-cake retaining

means removed; and Fig. 6 is a perspective view of the said compact or powder-cake retaining means.

Fig. 7 is an end view of the powder-box 5 or case, with its lid shown in its raised or opened relation.

Similar characters of reference are employed in all of the said above described views, to indicate corresponding parts.

- 10 Referring now to the several figures of the drawings, the reference character 1 indicates the complete powder-box made according to the principles of the present invention, the main body thereof comprising 15 a base 2 and side-walls 3, forming a box or case which is preferably of elongated configuration, the same being centrally divided by a laterally extending wall-member 4, suitably secured in position in any manner, 20 the said wall-member with the base and side-walls of the main body of the box or case, providing two compartments, as 5 and 6, in which the rouge-compact 7 and the face-powder compact 8 are adapted to be placed, 25 substantially as shown in the several figures of the drawings.

As shown, at the rear, the side-walls of the said body are provided with suitably constructed pintle-receiving ears or lugs 9, 30 between which is disposed a pintle-receiving ear or lug 12, extending from a portion of the surrounding rim or flange 11 of the cover or lid 10, a pin or pintle 13 being inserted in said registering ears or lugs, in the usual 35 manner, thus providing a desirable hinge-connection for closing the said cover or lid down over the main body of the box or case, as represented in Figs. 2, 3, 4 and 7 of the drawings. At its forward or front edge the 40 said lid or cover is made with a suitably formed catch, as 14, which is adapted to be forced over and sprung into separable holding engagement with a retaining lug or projection, as 15, located in the proper place and 45 extending outwardly from the front of the side-wall 3, as shown more particularly in Fig. 1, 5 and 7 of the drawings. Suitably secured within the inner space with which the said cover or lid 10 is provided, is a cor- 50 respondingly formed inlay 16, the same being provided with openings 17 and 18, back of which are placed mirrors 19 and 20, corresponding to the compartments 5 and 6, the 55 said inlay being also formed with a centrally disposed and laterally extending channel or groove 21, substantially as shown and for the purposes to be presently set forth.

In order to properly retain the rouge and face-powder compacts 7 and 8 within the 60 respective compartments 5 and 6 of the device, and, furthermore, when removing some of the portions of the compacts by rubbing, to prevent some of the contents or mixture of the one compact getting upon the other compact, and thereby spoil the color thereof, a

compact-retaining member or guard, such as is shown more particularly in Figs. 1, 2 and 6 of the drawings, is used in connection with the main body of the box or case, and especially with the dividing wall-member 4. 70 This retaining member consists, essentially, of a pair of side-flanges 22 and 23, which are connected with and extend in opposite directions from a supporting element or member 24, said element or member 24 being suitably channeled, as at 25, so as to be fitted in frictional contact upon the upper edge of the said wall-member 4, as clearly illustrated in Fig. 2 of the drawings. The said side or guard-flanges 22 and 23 are preferably of 80 the general marginal configuration shown, being provided with the arc-shaped edge-portions 26, which are turned down slightly, as at 27, so as to avoid sharp edges and the possibility of cutting or tearing the skin of 85 the fingers, when in the act of rubbing off some of the rouge or face-powder from the compacts within the compartments 5 and 6 and held in place by said flanges 22 and 23 which extend slightly over portions of the 90 respective compacts, substantially as indicated in Fig. 1 of the drawings. Other supporting members, as 28 and 29, may be provided, said members 28 and 29 extending at right angles, downwardly from the marginal end-portions of the respective guard-flanges. These members 28 and 29 prevent any possible tilting of the retaining member or guard, when supported upon the upper edge of the wall-member 4, but said members 100 28 and 29 are not absolutely necessary, and they may be omitted, if desired. When the lid or cover is closed down upon the main body of the powder-box, the supporting element or member 24 and the channel or 105 groove 21 are brought into registration, as indicated in Fig. 2 of the drawings, so that the closing down of the lid or cover upon the main body of the box or case will not be interfered with.

The objects and purposes, as well as the proper manipulation, of the device will be clearly understood from the foregoing description of the invention, and from an inspection of the several figures of the 115 drawings, and any further description of the same is therefore deemed unnecessary.

Of course we are aware that some changes may be made in the general arrangements and combinations of the several devices and parts as well as in the details of the construction of the said parts, without departing from the scope of the present invention as set forth in the foregoing specification, and as defined in the clauses of the claims 120 which are appended thereto. Hence we do not limit our invention to the exact arrangements and combinations of the said devices and parts as described in said specification, nor do we confine ourselves to the exact de- 125 130

tails of the construction of the said parts, as illustrated in the accompanying drawings.

We claim:—

- 5 1. A powder-box comprising a main box or case having side-walls and a dividing wall-member arranged to provide a plurality of compact-receiving compartments, and a retaining member within said box or case comprising oppositely extending side-flanges and a centrally disposed and channeled supporting member adapted to be mounted upon the upper edge of said wall-member, combined with a lid or cover for 10 said box or case, said lid or cover being provided with a channel with which the said supporting member is adapted to be brought into registration when said lid or cover is closed.
- 15 2. A powder-box comprising a main box or case having side-walls and a dividing wall-member arranged to provide a plurality of compact-receiving compartments, and a retaining member within said box or case comprising oppositely extending side-flanges and a centrally disposed and channeled supporting member adapted to be mounted upon the upper edge of said wall-member, combined with a lid or cover for 20 said box or case, said lid or cover being provided with a channel with which the said supporting member is adapted to be brought into registration when said lid or cover is closed.
- 25 3. A powder-box comprising a main box or case having side-walls and a dividing wall-member arranged to provide a plurality of compact-receiving compartments, and a retaining member within said box or case comprising a pair of laterally extending and concavely arc-shaped side flanges, said arc-shaped flanges being bounded by 30 downwardly extending marginal projections, and a centrally disposed and channeled supporting member between said side flanges adapted to be mounted upon the upper edge of said wall-member, combined with a lid or cover for said box or case, and an inlay secured within said lid or cover, said inlay being provided with a channel with which the said supporting member is adapted to be brought into registration when said lid or cover is closed.
- 35 4. A powder-box comprising a main box or case having side-walls and a dividing wall-member arranged to provide a plurality of compact-receiving compartments, and a retaining member within said box or case comprising a pair of laterally extending and concavely arc-shaped side flanges, said arc-shaped flanges being bounded by 40 downwardly extending marginal projections, and a centrally disposed and channeled supporting member between said side flanges adapted to be mounted upon the upper edge of said wall-member, combined with a lid or cover for said box or case, and an inlay secured within said lid or cover, said inlay being provided with a channel with which the said supporting member is adapted to be brought into registration when said lid or cover is closed.
- 45 5. A powder-box comprising a main box or case having side-walls and a dividing wall-member arranged to provide a plurality of compact-receiving compartments, and a retaining member within said box or case comprising a pair of laterally extending and concavely arc-shaped side flanges, said arc-shaped flanges being bounded by 50 downwardly extending marginal projections, and a centrally disposed and channeled supporting member between said side flanges adapted to be mounted upon the upper edge of said wall-member, combined with a lid or cover for said box or case, and an inlay secured within said lid or cover, said inlay being provided with a channel with which the said supporting member is adapted to be brought into registration when said lid or cover is closed.
- 55 6. A powder-box comprising a main box or case having side-walls and a dividing wall-member arranged to provide a plurality of compact-receiving compartments, and a retaining member within said box or case comprising a pair of laterally extending and concavely arc-shaped side flanges, said arc-shaped flanges being bounded by 60 downwardly extending marginal projections, and a centrally disposed and channeled supporting member between said side flanges adapted to be mounted upon the upper edge of said wall-member, combined with a lid or cover for said box or case, and an inlay secured within said lid or cover, said inlay being provided with a channel with which the said supporting member is adapted to be brought into registration when said lid or cover is closed.
- 65 7. A powder-box comprising a main box or case having side-walls and a dividing wall-member arranged to provide a plurality of compact-receiving compartments, and a retaining member within said box or case comprising a pair of laterally extending and concavely arc-shaped side flanges, said arc-shaped flanges being bounded by 70 downwardly extending marginal projections, and a centrally disposed and channeled supporting member between said side flanges adapted to be mounted upon the upper edge of said wall-member, combined with a lid or cover for said box or case, and an inlay secured within said lid or cover, said inlay being provided with a channel with which the said supporting member is adapted to be brought into registration when said lid or cover is closed.

In testimony that we claim the invention set forth above we have hereunto set our hands this 24th day of May, 1919.
